ASPHALT PENETRATION HEATER

Anton H. Heller, Levittown, N.Y., assignor to United Suffolk Corp., Hauppauge, N.Y., a corporation of New York

Filed Sept. 7, 1965, Ser. No. 86,892

Term of patent 14 years

(Cl. D60—1)

FIG. 1

FIG. 2

FIG. 3

FIG. 4

FIG. 5

FIG. 6

FIG. 1 is a side view of the asphalt penetration heater showing my new design,

FIG. 2 is a front view,

FIG. 3 is a side view opposite from that shown in FIG. 1,

FIG. 4 is a rear view,

FIG. 5 is a view of my asphalt penetration heater with the heater elements in a vertical position, and

FIG. 6 is a top plan view of FIG. 1.

The dominant features of my design reside in the portions shown in broken lines.

I claim:

The ornamental design for an asphalt penetration heater, substantially as shown and described.
